UNITED STATES PATENT OFFICE.

CHARLES W. LYON, OF PHILADELPHIA, PENNSYLVANIA, ASSIGNOR TO.
E. F. HOUGHTON & CO., OF SAME PLACE.

PRESS FOR FORMING PICKER LUG-STRAPS.

SPECIFICATION forming part of Letters Patent No. 633,870, dated September 26, 1899.

Application filed March 21, 1899. Serial No. 709,941. (No model.)

To all whom it may concern:

Be it known that I, CHARLES W. LYON, a citizen of the United States, residing in Philadelphia, Pennsylvania, have invented Improvements in Presses for Forming Picker Lug-Straps, of which the following is a specification.

My invention consists of a press for the manufacture of picker lug-straps, such as is shown and described in my Patent No. 620,469, dated February 28, 1899, the object of my invention being to retain the strap in its proper position in the outer die while the bent end of the strap is being subjected to the pressure of the inner die.

In the accompanying drawings, Figure 1 is a perspective view of a lug-strap press constructed in accordance with my invention. Fig. 2 is a longitudinal section of the same. Fig. 3 is a sectional plan view on the line *xx*, Fig. 2; and Fig. 4 is a view illustrating a modified construction of part of the machine.

The press shown in the drawings comprises a base 1, with rounded socket 2 for the reception of the rounded end of the lug-strap and an upwardly-projecting flange or side plate 3 for bearing against one side of said strap, a detachable side plate 4 fitting between opposite end wings 5 of the press and bearing against the other side of the strap, said plate being acted upon by a cam 6, hung upon a pin 7, which is carried by said wings 5.

The inner die-block 8 is acted upon by a cam 9, hung upon a pin 10, carried by the upper ends of the wings 5, and through a slot 11 in the upper portion of said inner die is free to move vertically a slide 12, having at its opposite ends plates 13, which act as end presser-plates for the strap, the slide 12 being depressed by means of a spring 14, inserted between the same and a plate 15, which closes the upper end of an opening formed in the die-block 8 for the reception of said spring. The die-block 8 and presser-plate 4 being removed from the press, the cemented strips of leather, with interposed filling-piece, which are to form the lug-strap, are bent around the inner die 8, the end presser-plates 13 insur-

ing the proper centering of the strap on the die, with the thickened portion of the same in position at the indented lower end of the die. The die, with the strap bent around it, is then introduced into the press. The side plate 4 is inserted and the cam 6 moved so as to thrust said plate inward and properly confine the strap laterally. The cam 9 is then operated so as to force the inner die 8 downward, and thereby impart the desired forming and hardening pressure to the inner face of the bent end of the strap, the full pressure of the inner die being concentrated against said bent end, owing to the fact that the opposite sides of the strap are so confined that they cannot expand laterally.

I have shown my invention as embodied in a single press; but it will be evident that a number of presses may be disposed side by side, a single shaft carrying all of the cams 6 and another shaft carrying all of the cams 9, so that each set of cams 6 or 9 can be moved simultaneously.

The necessity for removing the side plate 4 from the press for the introduction of the inner die 8 with the strap upon it may be overcome by making the upper cam 9 removable, so that the die 8, with its strap, can be introduced vertically between the side plates 3 and 4. This may be done by slotting the wing-plates 5, as shown at 16 in Fig. 4, for instance, so that the pivot-pin 10 can be slipped into and out of position.

Having thus described my invention, I claim and desire to secure by Letters Patent—

1. The combination in a lug-strap press, of the base and side plates, one of which is removable, said base forming a die for the outer portion of the rounded end of the lug-strap, a cam for moving the said side plate inward, a detachable inner die-block around which the strap can be bent before the block is placed in the press, and a cam for forcing said die-block down between the side plates, substantially as specified.

2. The combination in a lug-strap press, of the base and the side plates with the inner

die-block around which the strap can be bent, the spring-actuated presser-slide on said inner die-block, adapted to bear against the ends of a strap bent around the inner die-block so as to center said strap thereon, substantially as specified.

In testimony whereof I have signed my

name to this specification in the presence of two subscribing witnesses.

CHARLES W. LYON.
